[57] CLAIM

The ornamental design for stuffed toy bear, as shown and described.

DESCRIPTION

FIG. 1 is a right side view of a stuffed toy bear showing my new design;

FIG. 2 is a front view of the stuffed toy bear of FIG. 1; FIG. 3 is a left side view of the stuffed toy bear of FIGS. 1 and 2;

FIG. 4 is a rear view of the stuffed toy bear of FIGS. 1-4.

The top and bottom of the bear conform to that shown in the Figures.

FIG. 4

FIG. 1
